US0D1047572S

(12) **United States Design Patent** (10) **Patent No.:** **US D1,047,572 S**
(45) **Date of Patent:** **** Oct. 22, 2024**

(54) **CORDLESS BLENDER**

(71) Applicant: **Capbran Holdings, LLC**, Los Angeles, CA (US)

(72) Inventor: **Robert Finance**, Hartford, CT (US)

(73) Assignee: **Capbran Holdings, LLC**, Los Angeles, CA (US)

(**) Term: **15 Years**

(21) Appl. No.: **29/896,829**

(22) Filed: **Jul. 7, 2023**

(51) LOC (14) Cl. **31-00**

(52) U.S. Cl.

USPC **D7/378**

(57) **CLAIM**

The ornamental design for a cordless blender as shown and described.

DESCRIPTION

FIG. 1 is a perspective view of a cordless blender showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof; and,

FIG. 7 is a bottom view thereof.

The broken lines in the figures are included for the purpose of illustrating portions of the cordless blender and form no part of the claimed design.

1 Claim, 6 Drawing Sheets
